COP WINDING FRAME

Wilhelm Reiners, Gladbach-Rheydt, and Gustav Kahlisch, Rheydt, Germany, assignors to W. Schlafrhorst & Co., Gladbach-Rheydt, Germany, a corporation of Germany

Application February 24, 1936, Serial No. 65,484
In Germany March 4, 1935

6 Claims. (Cl. 242—32)

All the existing cop winding frames may be considered to belong either to one or the other of the following two distinct groups, namely, on the one hand those in which a certain number of spindles is interdependent in so far as the cop formation is synchronous for all the spindles of the particular group, or on the other hand the formation of the cop may be for each spindle quite independent of the building-up of the cop on the rest of the spindles.

The first group of machines in which the cop formation is synchronous for all the spindles of a particular group has the following advantages over the machine of the second group; easier manipulation, a smaller number of manual operations, therefore a higher production per operative and consequently cheaper wages. On the other hand, it has mainly drawbacks leading to the serious fault of sloughing in the shuttle. If an end breaks on any of the spindles, the regular formation of the cop will be interfered with and experience has shown that even if the cop is subsequently filled-up on an auxiliary machine, there is a great danger of sloughing in the shuttle on account of the difference in the density of the cop body.

In those machines in which all the yarn guides of the group move simultaneously in the same fashion with regard to their spindles, there will also be a zone of uneven density with the same danger of sloughing in the shuttle, because in the case of an end having failed the yarn guides will have proceeded for a certain distance before the said end has been knotted and the spindle re-started.

The object of the present invention is to provide a machine in which the advantages of the methods are combined and their disadvantages eliminated.

With this object in view the group system of operation is adopted but with the novel feature that the several cops are built up independently of each other, the traversing movements for producing the successive layers being independently controlled. Those cops which are not completely wound, due to rupture or failure of yarn, may remain in position in the machine when the other cops are doffed, or they may be returned to the machine after doffing, for completion in the course of the next winding operation.

The mechanism provided enables the winding of each batch to be started simultaneously, but with each spindle operating thereafter to build up its cop independently of the working of the other spindles.

Means may be provided for collectively doffing the cops, but with an arrangement enabling incompletely wound cops to be left in position. For this purpose there may be an arrangement whereby the doffing mechanism is disconnected from the spindle mechanism during the winding operation, and whereby its several units only come into operation, after the winding, if the respective cops are fully wound.

This device may be amplified by providing means whereby the several cop tube carriers of the donning and doffing device may be put out of operation separately.

Other features of the invention are described hereinafter and specifically pointed out in the appended claims.

One embodiment of the invention is shown in Figs. 1 to 9 of the accompanying drawings,

Fig. 1 being a side view, with parts in section, showing one of the spindle units.

Fig. 2 a plan view of part of the group of spindles.

Fig. 3 is a fragmentary elevation, with parts in section, of a spindle with appurtenant thread guide mechanism and counter support.

Fig. 4 is a plan view of the parts shown in Fig. 3, with the cop slid out on the spindle.

Fig. 5 is a view similar to Fig. 4, but with the knife and doffing device moved into operative position.

Fig. 6 is a fragmentary section at right angles to Fig. 5 showing the knife and doffing devices.

Fig. 7 is a plan view similar to Fig. 4 showing an empty cop tube being mounted upon the spindle.

Fig. 8 is a view similar to Fig. 7 with the spindle and new cop tube mounted thereon withdrawn from the top tube holder.

Fig. 9 is a view similar to Fig. 8, with the parts ready to begin winding.

Another embodiment is shown in Figs. 10 to 20,

Fig. 10 being a side view of one of the spindles, and

Fig. 11 a plan view of a group.

Fig. 12 is a fragmentary vertical section at right angles to the spindle of the machine shown in Fig. 10, showing the thread guide devices in front elevation.

Figs. 13 and 14 are views similar to Fig. 12, showing the parts in two other positions.

Figs. 15 and 16 are side views of donning and doffing mechanism.

Fig. 17 shows in front elevation and Fig. 18 in plan, a device for deflecting such cop tube car-

riars as appertain to spindle units occupied by cops which are not fully wound.

Fig. 19 is a front elevation of a device similar to Fig. 17, with an additional latch.

Fig. 20 is a front elevation of the mechanism actuating the thread guides of a group of spindles.

Referring first to the construction shown in Figs. 1 to 9, the spindles of the group are all driven by a common shaft 1, connected by a clutch to the motor in the usual way, and provided with a hand wheel 79 so that it can be given a number of turns by hand when required. The drive is transmitted to spindles 4 by pairs of bevel wheels 2, 3. Each spindle 4 is both rotatable and slidabile in its bearings 5, 6. The drive between the gear 2, 3 and the spindle is through a cone clutch 7, 8. A spring 9 tends to hold the two clutch members 7, 8 in engagement. The clutch is disengaged by means of a three-armed lever 10, 11, 12. A spring 13 connected at one end to the arm 11 and at its other end to an arm 14 on the spindle bearing 6 tends to hold the lever 10, 11, 12 in its disengaging position. The lever is, however, prevented from moving to disengaging position during the winding operation by a double armed lever 15, 16 pivotally connected to the bearing 6. The arm 15 of the lever 15, 16 extends upwards into proximity with a thread detector 18, 19 pivoted at 17 to the bearing arm 14. This thread detector is held in the position shown in Fig. 1 by the yarn which is being wound. If the yarn breaks or the supply becomes exhausted the nose 19 on the detector 18, 19 engages the double armed lever 15, 16 and rotates it so that the clutch lever 10, 11, 12 is released. The clutch 7, 8 is consequently disengaged. The spindle 4 carries at its left hand end a yoke 21 with a bearing 22. This yoke 21 is fixed at its lower part 23 to a rack 24. The latter is guided at 25 and 26 for sliding movement. A pinion 27 engages with the rack, and is rotatable on a shaft 28 common to the group of spindles, lateral movement of the pinion being prevented by collars 29, 30 (Figs. 1 and 2). The collar 30 is provided on its periphery with a projection 31. The pinion 27 has cast thereon a ring 32, to the periphery of which is connected at 34 a chain 33, so that the latter tends under the influence of a weight 35 to rotate the pinion 27. Cast on the inside of the ring 32 is a projection 36, in the plane of the projection 31 on the collar 30. The shaft 28 is mounted on the frame 37 in bearing arms 38, and is rotatable by means of a hand wheel 40. A bracket 41 is fixed to the right hand end of the rack 24 and carries a bar 42. On said bar is mounted an adjustable striker 43, which is adjusted according to the length of the cop 44 to be wound. When the cop attains the prescribed length the striker 43 abuts against the lever 15, 16 and thereby rocks the latter so that the clutch lever 10, 11, 12 is released, whereby the clutch 7, 8 is disengaged.

Fixed to a rod 45 common to the group of spindles are cop cones 46, one for each spindle, said cone when in operative position being coaxial with the spindle 4, as shown in Fig. 1. The cone 46 is held against rotation by arms 47, 48 and 70 remains stationary during the winding operation. To enable the rod 45 to be conveniently shifted longitudinally a lever system 122 is provided at one end of the rod, said lever system being connected to the shaft 45 through the medium of 75 a collar 122a, and the axial movement of shaft

45 is limited by a collar 122b coaxing with a bearing 123a. A shaft 50 is mounted on the frame for rocking movement and carries at each cop position a bracket 51 in which is fixed the thread guide 52. A yoke 53 embraces the rocking 5 thread guide bracket 51. Between the latter and the boss of the yoke 53 a spiral spring 54 is arranged on the shaft 50, one end of said spring being connected to the yoke 53 and the other end to the thread guide bracket 51, the spring 54 thus forces the thread guide bracket 51 against the yoke 53. The shaft 50 rocks with its thread guides 52 backwards and forwards in accordance with the traverse of the thread. This movement may be produced by means of a gear 58, 57, 56, 55, 59, 61, 60, 50 arranged at the end of the group and driven by the main shaft 1.

Inasmuch as all the thread guides 52 of a group of spindles are operably connected to the shaft 50 they are all moved together to produce the thread guiding movement for the whole group of cops. In the event of thread breakage or the thread supply becoming exhausted, to enable a new thread to be readily threaded into the guide 52 at the corresponding cop unit, notwithstanding the reciprocation of the thread guide, which is frequently rapid, the thread guides 52, as previously mentioned, are not screwed fast to their common shaft 50, so that owing to the resiliency 25 of the spring 54 one can be prevented from reciprocating with the others, if the handle 63 be held for a moment while the thread is being fed into the thread guide. A drop latch 65 may also be provided adjacent the cop cap cones 46, 47, 48, 35 said latch being adapted to be swung back during the winding operation but swung into the position shown in Figs. 1 and 2 for the purpose of stopping the thread guide 52, so that when the latter swings over to the right to its extreme end position it passes under the hook of the latch 65 and is held there. On the spindle 4 is a boss 66 the right hand end of which serves as an abutment for the cop tube or cop to be wound. Said boss has a groove 67 which serves to anchor the commencement of the thread for the new cop, 45 and it is also provided with two notched or roughened ring shaped flanges 68 with an intermediate groove 69. A bracket 70, one for each cop unit, carrying a thread severing knife 71 is 50 fixed on the sliding shaft 45 carrying the cup cones 46. The bracket 70 is so shaped and dimensioned at its upper end 72 carrying the thread severing knife 71 that it is able to enter the annular groove 69 in the spindle boss 66. On 55 one end of the rod 50 is a lever 73 by means of which all the thread guides of a group may be rocked.

Above the spindle clutch 7, 8 there is a rotatable shaft 74 which is common to all the cop units 60 and is provided at each cop position with a cam 75. A handle 76 may be fixed to one end of said rod, as shown in broken lines in Fig. 1. By moving this lever 76 and its shaft 74 with the cams 75 all the cop units can be thrown into operation, 65 due to the consequential engagement of their clutches 7, 8 by the levers 10, 11, 12, the detent lever 15, 16 then holding the parts in this position.

A cop tube trough 78, one for each cop unit, is 70 fixed to the shaft 45. All the troughs 78 appertaining to a group of cops thus slide with the shaft 45.

The operation of the apparatus according to the first constructional example will be readily 75

understood by reference to Figs. 1 to 9. One of the cops 44 (Fig. 1) is almost completed. The striker 43 of the rod 42 is already in engagement with the detent lever 15, 16. Shortly afterwards 5 the clutch lever 10, 11, 12 becomes disengaged from the shoulder on the detent lever 15, 16, the spindle is thus thrown out of operation independently of the other spindles which may possibly not have advanced so far. For instance, as shown in 10 Fig. 2, the centre cop is shown as having remained behind due to a defect in the winding. The shaft 28 is then turned by means of hand wheel 40 so that the projections 31 on the several collars 30 engage with the appurtenant projections 36 on the rings 32, and as a result all the racks 24 are shifted by their pinions 27 which causes all the spindles to be moved axially so that the cop chases are moved clear of their cup cones 46. By means of the lever 73 all the thread guides 20 52 on the common shaft 50 are swung over from the position shown in Fig. 1 to the position shown in Fig. 3. The cones 46 (Fig. 4) are moved with their shaft 45 away from the axis of the spindles 4, and the latter are pushed forwards, by rotating hand wheel 40 clockwise, until the thread guides 25 52 are opposite the run-on grooves 67 in the spindle bosses.

Prior to this, all the spindles were clutched to the common drive of the group by the separate 30 device 74, 75, 76 (Fig. 1). As the spindles are pushed out to the position shown in Fig. 3 they are rotated a few times by the simultaneous operation of the hand wheel 78 (Fig. 2) of the main drive shaft 1, so that the end of the thread 20 winds itself in the form of an extended helix 35 around each cop and is anchored by additional convolutions 80 (Fig. 5) in the run-on groove 67, this end of the thread passing transversely across the annular groove 69.

The shaft 45 is shown in Fig. 5 as having been slidden and rocked to such an extent that the brackets 70 thereon with the severing knives 71 have entered the annular groove 69 in the spindle boss, so that first of all the ends of the threads of the bobbins are severed from the starting threads 80 for the new set of bobbins anchored in the groove 67. At the same time the parts 72 of the brackets 70 engage with the groove 69, as shown in Fig. 6. The spindle head 66 is slideable on the squared part of the spindle 4.

All the spindles are then again retracted until the cop with its tube is completely released, when it drops into a collecting container or onto a travelling conveyor band. To enable this doffing of the cops from the body of the spindle to be effected by the pushing back of the spindles, the holder 72 of the bracket 70 still engaging in the groove 69 in the spindle boss holds back the spindle head.

Now the shaft 45 with the cones 46 is pushed along (Fig. 7) until the troughs and the empty cop tubes carried thereby are coaxial with the spindles 4 and the brackets 70, likewise moved, have released the spindle boss 66. Meanwhile 10 (Fig. 8) all the spindles remain in retracted position. By operation of the hand wheel 40 the spindles are now pushed forward into the empty cop tubes and then retracted again. By sliding the shaft 45 back again to starting position the spindles 4 are brought with their cop tubes opposite the cones, and are moved forward to their original operative position (Fig. 9) by means of hand wheel 40. The thread guides 52 are also moved from their disengaged position shown in Fig. 3 to operative position.

The machine is now ready to operate again, the device 74, 75, 76 being still in the position in which all the spindles are clutched to the drive.

The thread detectors 18 are also returned to the position shown in Fig. 1 by the tension of threads 28, and the device 74, 75, 76 can be returned to the position shown in Fig. 1. The building up of the cops commences again, each cop being built up independently of the other.

Constructional example II (Figs. 10-20) 10

In this constructional example for carrying the new method into effect the machine is of the so-called spindle-less type wherein the cops 44 are clamped in individual mounts each consisting of a driving spindle boss 66 and a counter holder 126. The automatic and independent building movement is effected by the thread guide being moved for every new winding layer to the extent of the thickness of the thread by a feeler 20 wheel 127 on a screw spindle 128. The traverse movement is transmitted to the thread guides 52a with their screw spindles 128 for all the spindles of the group by the common shaft 50a, which is rocked by a cam disk 59a (Fig. 20) 25 fixed to a shaft 55a driven from the main shaft 1 through a gear not shown in the drawings. The cam 59a acts upon a roller 61a of a lever 60a rockably mounted on shaft 50a and urged by a spring 62a in the direction which holds its 30 opposite end 60b against a lug 73b on lever 73a fixed to shaft 50a.

The shaft 50a carries loose rock levers 129 which are caused to rock with said shaft by reason of their being spring pressed against a 35 rocking yoke 53a which moves with the shaft. The rock levers 129 transmit their movement through the screw spindles 128 to a lever 130 which is free to rock on the stationary shaft 131.

The lever 130 serves to guide the movement 40 of the screw spindle 128 and it also enables the thread guide movement to be interrupted for a short time, by means of its handle at the upper end, so that after an irregularity in the winding on one of the spindles the thread may 45 be readily laid in the guide 52a, due to the rock lever 129 being resiliently connected with rock shaft 50a.

The bobbin drive spindle 4a is mounted in the spindle bearings 5a, 6a. The spindle is driven 50 by the common shaft 1 and the pair of gear wheels 2a, 3a for each cop unit.

The wheel 3a is mounted between the bearings 5a, 6a of the spindle support, and is connected to and runs on the same bush as one 55 clutch half 1a, the other clutch half 3a being slideable by means of the clutch lever 10a, 11a (Figs. 10 and 17). Said lever 10a, 11a is loose on the shaft 14a which is common to the group. On the shaft 14a there is also fixed for each 60 cop unit a cam 75a with a pin located opposite the nose 10a on the clutch lever 10a, 11a. To shaft 14a is fixed a hand lever 16a by means of which all the cop units of a group are set in motion simultaneously, said hand lever being 65 rocked to the right so that the cams 75a abut against the nose 10a of the clutch lever 10a, 11a and cause the spindle clutches to engage. A thread severing member 124 for each cop unit is also fixed to shaft 14a. To the clutch lever 70 10a, 11a is connected a rod 133 the other end of which is guided in a bracket 134. This rod is provided in proximity to the bracket 134 with a notch and shoulder 135. During the winding operation this shoulder is held by a tension 75

- spring 13a on the lever 11a against a stop on the bracket 134. To throw individual cop units out of operation, the rod 133 is lifted to bring the shoulder 135 clear of the stop on bracket 134.
- 5 This is also effected automatically when the control pin 52b abuts against the nose 133a on the rod 133. The same rod 133 also serves, in the case of thread breakage, to stop the spindle through the medium of the detector 18a by pin 18b, the latter also lifting the rod 133 with its shoulder 135 clear of stop 134.
- In this constructional example means are also shown for preventing replacement of cops which are not fully wound, so that winding of these 15 cops may be completed during the winding of the next set of cops. To this end the counter heads 126 are extended at their rear ends 126b so that they project beyond the bearings 137, said heads 126 with the spindles 4a holding the tubes 81 20 or the cops 44 in position and being axially spring loaded in their bearings 137 on the transverse bearer 139a. The extension 126b has a notch 138. Brackets 140 are fixed to a rail 139 common to all the cops, and said brackets carry a 25 shaft 141 on which are mounted individually operable coupling devices in the form of drop latches 142, 143, one for each cop unit. The bearing 137 carries a slidable rod 144 the length of which is such that on the cop attaining its 30 full length said rod 144 contacts with the member 145 of the thread guide and is consequently moved axially so that the latch 142 drops to the position indicated in Figs. 15 and 16, its nose 146 engaging in the groove 138 of the counter bearing 126. To release all the fully wound cops 35 from their winding position when the cops are replaced, the rails for the drop latch device 140, 141, 142 are fixed to brackets 147 which are fixed to the outer end of slidable bars 148. These 40 bars 148 are mounted on the frame of the machine 37a at 149 and 150. The sliding movement of bar 148 may be produced by operation of a rock shaft 154 bearing cranks 153, each engaging by a lug 152 in the groove of a sleeve 45 151 fixed to bar 148, as shown in Fig. 10.
- The thread guides 52a are moved collectively and simultaneously from their limit position to the original position shown in Fig. 16, that is the position at which the thread is anchored, by the 50 following device.
- For each cop unit there is a rack 157 slidable in bearings 155, 156 (Fig. 10) and meshing with a pinion 159 fixed to the shaft 158. The shaft 158 and the racks movable thereby may be 55 operated by hand, or by control mechanism, not shown. The racks 157 are provided at their front ends with a notch 160 in which a double armed latch 161, 162 pivoted at 163 to the thread guide bracket 145 engages when the cop attains its 60 full length (Figs. 12-14). To the counter bearing 137 is fixed a rod 164 the length of which is such that when the cop is completely wound one arm 161 of the latch 161, 162 abuts against the rod 164. The latter causes the pawl to engage in the notch in the rack 157. During this 65 movement of the latch the nut of the feeler wheel is forced out of the screw thread on the rod 128 by engagement of latch 161 with the pending foot 166 of a yoke 165 which embraces the nut of the feeler wheel or builder disc 127 at its upper end and is pivoted at 167 on the shaft of the thread guide 145. Then, by operating 70 the common shaft 158, all the racks 157 and the thread guides 52a therewith can be returned 75 to their initial position (Fig. 16), that is to

say, to the position at which the thread is anchored. Thereupon all the cop units are thrown into operative connection with their driving means by the common gear 74a, 75a, 76a.

The spindles 4a are then rotated a few times 5 by rotating the hand wheel on the drive shaft 1, so that the thread for the new set of cops to be wound is secured to the spindle boss in groove 67. The ends of the threads are then severed by the knives 124. The drop latches 142, 143 10 for the fully wound cops all engage with their noses 146 in all the notches 138 in the cop counterheads 126. By operating a hand wheel on shaft 154 the supporting means for the latches 142 carried by shaft 148 are moved outwards, 15 and the cop counterheads 126 likewise, so that all the finished cops 44 are released; these cops may drop onto the endless conveyor band 169 in the open container 168, whilst any incompletely wound cops remain in their winding positions due 20 to their coupling with the cop doffing device having remained disengaged.

As shown in Figs. 17 and 18, the bare cop tubes 81 disposed in troughs 78a carried by the arms 178a (Fig. 10) are swung up to the skewering position by the cranks 170 through the medium of the control rod 170c. The trough carriers 178a are pivoted at 171 to their brackets 172a and are held in upright position by springs 172. The brackets 172a are mounted on transverse bars 170a connected to a guide member 179b. At the upper ends of the trough carriers 178a are inclined abutments 173 which in tilting upwards engage with the counterheads 126 of the still incompletely wound clamped in 35 cops and then move away laterally so that no bare tube can reach the clamping in position at this point.

Fig. 19 shows means whereby the tube carriers 78a may be manually kept away from the 40 tube feed position by operation of a latch 177 mounted on the common bar 170a for the tube carriers 78a, there being one of the latter to each cop unit. During the return of the clamping in device 140, 141, 142, 143 the bare tubes are 45 again clamped in between the spindle drive heads and the counterheads. Then, by means of the hand lever 174 and the fingers 175a on the common shaft 141 all the latches 142, 143 are rocked back to the re-set position shown in Fig. 10. 50

Obviously in lieu of the stationary resilient tube carriers as provided for each cop-unit, the tube carriers may be arranged on endless conveyor means in known manner, so that the cop tubes are fed from a magazine, for instance at 55 the end of the machine, to the several cop units.

Finally, all the thread guides 52a are brought to their starting position for the simultaneous commencement of winding. The throwing into operation of all the cop units simultaneously 60 causes the thread guides 52a to swing up from the position shown in Fig. 16 and by the latch 161, 162 to strike the upper pin 176, so that the nut of the wheel 127 engages again with the screw thread on its spindle 128. 65

The building up of each cop independently commences again.

It will be understood that we do not limit ourselves to the particular constructions shown, since they may be modified within wide limits 70 without departing from the spirit of the invention.

We claim:

1. In a machine for winding bobbins, a group of spindles, common driving means for said spin- 75

dles, means for releasing said spindles individually from said driving means, means for coupling said spindles in unison to said driving means, threaded rods parallel to said spindles, 5 yarn guide devices comprising builder discs mounted on said rods, contact means engageable by said yarn guide devices for separately operating said releasing means, means for releasing said builder discs from the threads of 10 said rods, and means for restoring said thread guide devices in unison to the base of the bobbins.

2. In a machine for winding bobbins, a group of spindles, common driving means for said spindles, means for releasing said spindles individually from said driving means, means for coupling said spindles in unison to said driving means, threaded rods parallel to said spindles, 15 yarn guide devices comprising builder discs mounted on said rods, contact means engageable by said yarn guide devices for separately operating said releasing means, means for releasing said builder discs from the threads of 20 said rods, means for restoring said thread guide devices in unison to the base of the bobbins, and means controlled by the building up of the bobbins for individually coupling said thread guide devices to said restoring means.

3. In a machine for winding bobbins, a group 30 of spindles, threaded rods respectively adjacent to said spindles, yarn guide devices for the respective spindles comprising builder discs having means engaging the threads of said rods, means operable by the travel of the individual yarn 35 guide devices for releasing said builder discs from

the threads of said rods, and means for restoring said yarn guide devices to the base of the spindles in unison.

4. In a machine for winding cops, a group of individual mounts for a plurality of cops, and 5 means for doffing the cops in unison from said mounts including individually operable coupling devices engageable with the respective mounts in preparation for doffing.

5. In a machine for winding cops, a group of 10 individual mounts for a plurality of cops, means for doffing the cops in unison from said mounts including individually operable coupling devices engageable with the respective mounts in preparation for doffing, and means controlled by the 15 progress of the winding of each cop for engaging the coupling devices with the respective cop mounts, whereby the doffing means are prevented from operating upon incompletely wound cops.

6. In a machine for winding cops, a group of 20 spindles, thread guides associated with the respective spindles, means associated with each spindle and comprising a part engaging the thread winding on the appurtenant spindle for 25 causing a progressive relative movement of the appurtenant spindle and thread guide, means terminating said progressive relative movement on each spindle independently of the others when the desired length of cop has been wound, and 30 means operable to restore the original relative positions of said spindles and yarn guides in unison.

WILHELM REINERS.
GUSTAV KAHLISCH. 35
